UNITED STATES PATENT OFFICE.

JOHN S. LOVRINOVICH, OF HOBOKEN, NEW JERSEY.

TRANSOM-OPENER.

1,151,206.

Specification of Letters Patent. Patented Aug. 24, 1915.

Application filed April 1, 1915. Serial No. 18,447.

To all whom it may concern:

Be it known that I, JOHN S. LOVRINOVICH, a citizen of the United States of America, and a resident of Hoboken, Hudson county, 5 and State of New Jersey, have invented certain new and useful Improvements in Transom-Openers, of which the following is a specification, reference being had to the accompanying drawings, forming a part 10 thereof.

My invention relates to builders' hardware and has special reference to transom operating devices.

One object of my invention is to provide 15 a simple, durable and relatively inexpensive device of the aforesaid character that shall be easy to manipulate and adapted for mounting the transom either to swing on a central pivot or on a pivot at or near its 20 lower edge.

Other objects and advantages of my invention will be set forth hereinafter, and in order that my invention may be thoroughly understood, I will now proceed to 25 describe the same in the following specification, and then point out the novel features thereof in appended claims.

Referring to the drawings, Figure 1 is 30 a front elevation of a door and transom equipped with a transom operating device arranged and constructed in accordance with my invention. Fig. 2 is a side elevation of the same parts with the door frame shown in section. Fig. 3 corresponds to 35 Fig. 1 but shows the transom mounted to swing about a substantially central pivot instead of a pivot located near its lower edge. Fig. 4 corresponds to Fig. 2 but illustrates the arrangement of Fig. 3.

40 One of the novel details of my invention is shown on a larger scale in Fig. 5.

10 represents a door frame comprising uprights 11 a lintel 12 and a cross beam 13 at the top of the transom opening. The 45 door opening is shown as provided with a door 14, a transom 15 being mounted in the transom opening between the lintel 12 and the top beam 13.

The transom is mounted and operated by 50 apparatus which embodies my invention and which comprises a pair of stationary brackets 16 and 17, each having a through slot 18 and a bifurcated lug 19; removable pivotal brackets 20 and 20^a, an operating lever 30 55 and a link 40.

The stationary brackets 16 and 17 are

preferably set in recesses provided in the door frame as clearly shown in Fig. 2, and the bifurcated lugs 19 extend outwardly from the base plates of the brackets in both 60 directions and are provided with perforations 21 and 22.

The brackets 20 and 20^a have angle plates 24 which are secured to the transom near its opposite ends as shown in Fig. 1, and 65 have lugs or ears 25. The pivotal bracket 20 is furthermore provided with a lug or ear 26 and is connected by a pivot pin 27 to the bifurcated upper end 41 of the link 40. The lug or ear 25 of bracket 20 extends into 70 the slot 18 of the stationary bracket 16, the bracket 20 being pivotally connected to the stationary bracket by a pin 28, which extends through the perforation 21 in the bifurcated lug 19 and through a correspondingly located hole in the lug 25. The bracket 20^a is similar to the bracket 20, except that the lug 26 is omitted, and it is similarly mounted on the stationary bracket 17. 80

The link 40 is interposed between the pivotal bracket 20 and the operating lever 30 and has a bifurcated lower end 42 which is connected to the lever by a pin 43. The lever is pivotally supported at 31 on a stationary bracket 32 which has a slot 33 and bifurcated lug 34. It is also provided with a toothed rack portion 35 which is adapted to be engaged by a pawl 35^a, the position of the lever and of the transom being thus 90 maintained as desired.

The lever 30 has an extension 36 which is connected to it by a pin and slot connection and is formed with the pocket 37 as clearly shown in Fig. 5. The arrangement of parts 95 is such that when the extension is pushed into place with the outer end of the lever extending into the pocket 37, it acts as a rigid part of the lever. But when it is pulled outwardly it is free to swing as indicated in Figs. 2 and 5 of the drawings, so that it will not extend so far out from the door frame.

100 Springs 50 are preferably mounted on the uprights 11 of the door frame below the stationary brackets 16 and 17 and are adapted to coöperate with projections 29 of the brackets 20 and 20^a when the transom is swung into its open position. The springs also assist in closing the transom and compensate to a greater or less extent for the increased lifting power necessarily applied 105 110

to swing the transom closed from its wide open horizontal position.

The link 40 may be adjusted to perfect the operation of the device, after the mechanism is attached to the transom and door frame, since it comprises a section 40^a having left and right hand threads at its ends. A nut 40^b is provided for locking the section 40^a after the link has been adjusted.

10 The utility of the second perforation 22 which is to be found in each of the stationary brackets 16 and 17 will now be explained. These perforations are so placed with reference to the outer surfaces of the 15 bracket plates that they lie in the central plane of the transom. When it is desired to mount the transom on a central pivot as shown in Figs. 3 and 4, the stationary brackets 16 and 17 are mounted in the 20 proper position as here indicated and the brackets 20 and 20^a are pivotally supported on the stationary brackets by mounting the pivot pins in the perforations 22 instead of in the perforations 21, the lugs 25 being 25 perforated to correspond to the perforations of the lugs 19.

The operation of the device will be understood from the foregoing description and a brief outline as follows will suffice: Referring particularly to Fig. 2 and assuming that the transom is partially open as here indicated, the extension 36 of the lever 30 may first be forced into position to constitute a rigid extension of the lever. It then 35 constitutes the handle which may be gripped by the operator and swung upwardly to close the transom. The movement of the lever about the pivot 31 is transmitted through the link 40 to the pivotal brackets 40 20 and 20^a. These brackets are consequently 45 swung about their pivots 20^a and carry the transom with it. The transom may be set in any desired position by swinging the pawl 36 into engagement with the desired notch 45 of the rack 35.

It is evident that structural variations may be effected within the spirit and scope of my invention, and I intend that only such limitations be imposed as are indicated 50 in the appended claims.

What I claim is:

1. A transom operating mechanism comprising a pivotal bracket adapted to be affixed to a transom, a stationary bracket 55 having means for supporting the pivotal bracket with axis in the plane either of the

center of the transom or of its outer surface and an operating lever connected with the pivotal bracket.

2. A transom operating mechanism comprising a pivotal bracket adapted to be affixed to a transom, a stationary bracket having means for supporting the pivotal bracket with its axis in the plane either of the center of the transom or of its outer surface, an operating lever, a link connecting the lever with the pivotal bracket and means for holding the lever in any one of a plurality of positions as desired. 60 65

3. A transom operating mechanism comprising a pivotal bracket adapted to be affixed to a transom, a stationary bracket having means for supporting the pivotal bracket in two different relations, a collapsible operating lever having an extension 70 75 connected to it by a lost motion connection and adapted to act either as a rigid part of it or to be swung freely with respect to it, and a link connecting the lever with the pivotal bracket. 80

4. A transom operating mechanism comprising a pivotal bracket having a perforated lug and adapted to be affixed to a transom with the perforated lug extending at right angles to the plane of the transom, a stationary bracket having a bifurcated lug and a slot between the parts of the lug, said bifurcated lug having perforations and adapted to coöperate with the perforated lug of the pivotal bracket, a pivotally supported operating lever and a connecting link between the lever and the pivotal bracket. 85 90

5. A transom operating mechanism comprising a pivotal bracket having a perforated lug and adapted to be affixed to a transom with the perforated lug extending at right angles to the plane of the transom, a stationary bracket having a bifurcated lug and a slot between the parts of the lug, said bifurcated lug having perforations and 100 adapted to coöperate with the perforated lug of the pivotal bracket, a pivotally supported operating lever and a connecting link between the lever and the pivotal bracket, said coöoperating lugs being adapted to receive a pivot pin constituting an axis for the transom either in the plane of its outer surface or in a central plane as desired. 105

In witness whereof I have hereunto set my hand this 30th day of March 1915.

JOHN S. LOVRINOVICH.
